UNITED STATES PATENT OFFICE.

ALBERT CARROLL BUTLER, OF CRANDALL, TEXAS.

OIL-BURNER.

No. 833,299.

Specification of Letters Patent.

Patented Oct. 16 1906.

Application filed October 6, 1905. Serial No. 281,667.

To all whom it may concern:

Be it known that I, ALBERT CARROLL BUTLER, a citizen of the United States, residing at Crandall, in the county of Kaufman and State of Texas, have invented a new and useful Oil-Burner, of which the following is a specification.

This invention relates to that class of burners which are adapted especially for the consumption of fuel, such as crude oil; and among the objects of the invention are to simplify and improve the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

In the accompanying drawings, Figure 1 is a sectional elevation of an apparatus embodying the invention. Fig. 2 is a sectional detail view, on an enlarged scale, of the burner.

Corresponding parts in both figures are indicated throughout by similar characters of reference.

An air-tank 1 of suitable dimensions is provided, upon which is supported a framework 2, carrying a casing 3, within which is accommodated a spring or other motor, the main driving-shaft of which has been shown at 4, said shaft carrying a pulley 5, from which motion is transmitted by means of a belt 6 to a shaft 7, supported for rotation in the framework 2 and carrying balance-wheels 8 and 9, the former of which is engaged by the belt 6. The wheel 8 also has a wrist-pin 10, connected by a pitman 11 with the piston-rod 12 of an air-compressor 13, the body or cylinder of which carries a guide 14 for the piston-rod. The cylinder of the air-compressor is connected by a pipe 15 with the lower end of the tank 1, within which air may thus be compressed and stored.

Adjacent to the air-tank 1 is an oil tank or container 16, the upper end of which is connected with the air-tank by means of a pipe 17, having a valve 18. Extending from the lower end of the oil-tank is a pipe 19, which is connected with and serves partially to support the burner-casing 20. The pipe 19 has a controlling-valve 21. The burner-casing 20 is cruciform, one of its laterally-extending

arms 22 terminating in a nozzle 23, having a discharge-aperture 24. The opposite lateral arm 25 is interiorly threaded for connection with a pipe 26, having a controlling-valve 27, the opposite end of the pipe 26 being connected with the air-tank. The upwardly-extending arm or cavity 28 of the burner-casing has a closure 29, which may be integral with the casing, and the downwardly-extending arm of the latter is interiorly threaded throughout, partly for connection with the pipe 19 and partly for the accommodation of a conical nozzle 30, the discharge-aperture of which, 31, is directed against the closure 29 of the arm 28.

The downwardly-extending arm of the burner-casing is designated 32. As the nozzle 30 is screw-threaded into the arm 32, its vertical position may be adjusted therein.

A constant air-pressure is maintained within the tank 1 by the compressor 13, which is operated by the motor within the casing 3. The valves 18, 21, and 27 are normally closed. By opening the valves 18 and 21 the oil contained in the tank 16 will be subjected to pressure, whereby it is caused to flow through the pipe 19 and past the valve 21 to the burner-casing, into which it is injected through the nozzle 30. The oil thus injected will impinge upon the closure 29 and be thereby deflected exteriorly upon the nozzle 30, which will be covered with a film of oil. The valve 27 being now opened will cause an inrush of air which will impinge upon the nozzle 30, thus atomizing and becoming intimately associated with the oil and forming a highly-combustible gas which is forcibly expelled through the aperture 24 of the burner-nozzle, at which point it may be readily ignited. In practice the burner-nozzle will be extended partly within the casing of a stove or furnace, where thorough combustion will take place, as will be readily understood. It will thus be seen that the burner-casing constitutes a mixing-chamber within which the air forcibly injected from the tank 1 will be carbureted by the liquid hydrocarbon introduced under pressure from the tank 16 through the nozzle 30. It is obvious that by providing a proper system of piping any desired number of burners may be connected with one set of tanks and air-compressing mechanism, said tanks being made of suitable dimensions and the air-compressor being sufficiently power-

ful to supply the number of burners included in the system.

Having thus described the invention, what is claimed is—

5. 1. A hydrocarbon-burner consisting of a casing having a horizontal air-passage terminating in a discharge-nozzle, an oil-inlet leading into said casing at the side thereof, an upwardly-disposed cavity located at the opposite side of the casing from said oil-inlet, a conical nozzle located in said oil-inlet and having its end disposed toward said cavity.
- 15 2. A hydrocarbon-burner consisting of a casing having a horizontal air-passage terminating in a discharge-nozzle, an oil-inlet leading into said casing at the side thereof, said casing having an upwardly-disposed cavity located at the opposite side from said oil-inlet, a nozzle located in said oil-inlet and having its end disposed toward said cavity and lying within the same.
- 25 3. A hydrocarbon-burner consisting of a casing having a horizontal air-passage terminating in a discharge-nozzle, an oil-inlet leading into said casing at the side thereof, said casing having an upwardly-disposed cavity located at the opposite side from said oil-inlet, an adjustable nozzle located in said oil-

inlet and having its end disposed toward said cavity.

4. A hydrocarbon-burner consisting of a casing having a horizontal air-passage terminating in a discharge-nozzle, an oil-inlet leading into said casing at the side thereof, said casing having an upwardly-disposed cavity located at the opposite side from the oil-inlet, a conical nozzle adjustably located in said oil-inlet and having its end disposed toward said cavity.

5. A hydrocarbon-burner consisting of a casing having a horizontal air-passage terminating in a discharge-nozzle, an oil-inlet leading into said casing at the side thereof, said casing having an upwardly-disposed cavity located at the opposite side from said oil-inlet, a conical nozzle screw-threaded in the oil-inlet and having its end disposed toward said cavity.

In testimony that I claim the foregoing as my own I have hereto affixed my signature in the presence of two witnesses.

ALBERT CARROLL BUTLER.
